UNITED STATES PATENT OFFICE.

DAVID F. VAUGHAN, OF RIVERTON, NEW JERSEY.

ANTICREEPER FOR RAILROAD-RAILS.

1,099,525.

Specification of Letters Patent.

Patented June 9, 1914.

Application filed December 16, 1913. Serial No. 806,962.

To all whom it may concern:

Be it known that I, DAVID F. VAUGHAN, a citizen of the United States, residing at Riverton, in the county of Burlington and State of New Jersey, have invented certain new and useful Improvements in Anti-creepers for Railroad-Rails, of which the following is a specification:

My invention relates to anticreepers for railroad rails, and particularly to that type thereof wherein a bar adapted to extend beneath a rail base is employed in conjunction with means on one end of the bar adapted to engage one side of a rail base and adjustable means on the other end of the bar adapted to engage the other side of a rail base and operative to clamp the anticreeper to a rail.

The object of my invention is to provide an anticreeper of the above general character, with a novel, simple, efficient and adjustable means on one end of the bar and operative to firmly clamp the anticreeper to a rail.

A further object of my invention is to provide a novel stop part adapted to engage a stationary part of a road bed, and to construct the parts of the anticreeper so that the stop part may be clamped between the bar and the bottom of the rail by operating said adjustable means to raise one end of the bar.

A further object of my invention is to construct the parts so that said adjustable means may be operated to raise one end of the bar and thereby spring it from a normal condition and cause it to firmly hold the anticreeper in position in tending to resume said normal condition; and a further object of my invention is to provide various novel features of construction and combinations of parts as will be hereinafter fully described and claimed.

In the accompanying drawings, illustrating my invention: Figure 1, is a side elevation of a portion of a railroad rail, a portion of a cross tie and my improved anticreeper applied to the rail. Fig. 2, is an elevation of the parts shown in Fig. 1, as seen from a position looking at one end of the rail. Fig. 3, is a plan view of the parts shown in Fig. 1. Fig. 4, is a view showing the relations of parts of the anticreeper to each other and to the rail in one position thereof during the application of the anticreeper to the rail. Fig. 5, is a

view of a modification of the locking member.

Referring to the drawings, 2 designates a portion of a railroad cross tie and 3 a railroad rail of usual construction. The cross tie 2 forms a stationary part of the road bed which supports the rail and over which the rail tends to creep under the well known conditions.

My improved anticreeper is applied to the base 4 of the rail 3, and, in its preferred form, is constructed as follows:

Extending transversely beneath the rail 3 is a bar 5 having a rail gripping part 70 or hook 6 formed on one end thereof which extends over one side of the rail base 4. The other end of the bar 5 also has a hook 7 formed thereon, comprising an upwardly extending portion 8 spaced from the adjacent side of the rail base 4, and an inwardly extending portion 9 extending over the adjacent side of the rail base 4. The distance between the portion 8 and rail gripping hook 6 is such that the rail base 4 may be 80 passed between the portion 8 and hook 6 after the portion 9 has been first passed over one side of the rail base.

Interposed between the hook 7 and the adjacent side of the rail base 4 is a locking member 10 which extends between the top of the rail base 4 and the hook portion 9, at 11, and which extends between the side of the rail base 4 and the hook portion 8, at 12; the part 11 serving to hold the portion 9 raised from the rail base 4, and the part 12 serving to maintain the rail gripping hook 6 in proper engagement with the rail base. The locking member 10 is movable longitudinally of the rail 3 into and from the hook 7, and one end of the member 10 has an inclined face 13 forming a wedge 14 on one end of the member. When the parts are being assembled, the member 10 is moved longitudinally of the rail, in the direction of the arrow, into the hook 7, and, during such movement, the wedge 14 engages the portion 9 of the hook 7 and raises the adjacent end of the bar 5. The member 10 has an upwardly-extending stop projection 15 adapted to engage one side of the portion 9 to limit the movement of the member 10 in the direction of the arrow while the parts are being assembled; and the member 10 also has an upwardly extending stop projection 16 at the wide end of the wedge 14 and adapted to engage the

other side of the portion 9 to prevent accidental movement of the member 10 in a direction opposite to the arrow, after the parts are assembled. When the parts are 5 assembled, the hook portion 9 rests on a horizontal face 17 of the member 10 between the two stop projections 15 and 16.

Arranged centrally beneath the rail 3 is a stop part 18 which is clamped between the 10 central portion of the bar 5 and the bottom of the rail 3, and which is adapted to engage the cross tie 2 and prevent the creeping of the rail. This stop part 18 comprises a horizontal body portion 19 between the rail 15 3 and bar 5, a plate or flange 20 extending downwardly from one end of the body portion 19 adjacent the cross tie 2, and a stop projection 21 extending downwardly from the other end of the body portion 19 and between which and the tie 2 the bar 5 is located.

The side faces of the body portion 19 converge in the direction away from the tie 2 forming a wedge, so that if the bar 5 attempts to move with the rail when it tends to creep, the wedge shaped body 19 will be forced between the end portions of the bar 5 which extends upwardly from the sides of the wedge in a manner to separate the 30 end portions of the bar 5 from the rail 3 and thereby cause the stop part 18 to be more firmly clamped between the bar and the rail.

The stop projection 21 serves to prevent 35 the bar 5 from moving with the rail 3 in a direction away from the tie 2 without carrying the stop part 18 therewith, as the rail 3 expands or contracts longitudinally, under different weather conditions; as frequently the ballast in the road bed engages the stop part 18 and makes it difficult for the stop part to move with the rail, particularly is this true when water is frozen in the ballast.

40 The bar 5 is preferably formed of spring metal and its normal condition is as shown in Fig. 4. In applying the anticerper to the rail the bar 5 is first placed in the position shown in Fig. 4, with the rail gripping hook 6 against the top of one side of the rail base, the top of the central portion of the bar 5 against the bottom of the body 19, the top of the body 19 against the bottom of the rail and the hook portion 9 near the top of one side of the rail base. The locking member 10 is now driven into the hook 7. The point end of the wedge 14 first enters between the hook portion 9 and top of the rail base 4, and, as the member 10 is driven in the direction of the arrow, the wedge 14 forces the adjacent end of the bar 5 upwardly and springs it from its normal condition shown in Fig. 4 to the condition shown in Fig. 2. The member 10 is driven 45 in the direction of the arrow until the hook

portion 9 rests upon the horizontal face 17 of the member 10 between the two stop projections 15 and 16, the hook portion 9 springing over the projection 16 as it passes thereunder. Thus the bar 5 will, in tending to 70 resume its normal condition, press the hook 9 and member 10 down firmly upon the rail base 4, and press the body 19 of the stop part 18 firmly up against the bottom of the rail. This spring action in the bar 75 5 is an important feature of my invention and it compensates for any irregularity between the different parts and maintains all parts of the anticerper in constant readiness for action at all times and under all 80 conditions.

The spring action in the bar 5, while important, is not essential in every form of embodiment of my invention; and, when a bar having no spring action is used the stop 85 projection 16 is omitted and the inclined face 13 of the member 10 extends from the point end of the wedge 14 to the stop projection 15, as shown in Fig. 5, and the portion 9 of the hook 7, rests at all times upon 90 the inclined face 13 of the member 10.

I claim:

1. The combination with a railroad rail having a base, and a stationary part of a road bed, of an anti-creepers adapted to engage said stationary part and comprising a spring bar extending beneath the rail and provided with a part engaging the bottom of the rail, one end of said bar having a rail gripping part extending over one side 100 of the rail base, and a locking member engaging the other end of said bar and the top of the other side of the rail base, said member having a beveled face extending in the direction of the length of the rail and adapted to engage and raise one end of said bar when said member is moved longitudinally of the rail, and said bar being sprung from a normal condition and pressing said rail gripping part and said member downwardly 110 and pressing said part engaging the bottom of the rail upwardly in tending to resume said normal condition.

2. The combination with a railroad rail having a base, and a stationary part of a road bed, of an anti-creepers adapted to engage said stationary part and comprising a spring bar extending beneath the rail and provided with a part engaging the bottom of the rail, one end of said bar having a rail 115 gripping part extending over one side of the rail base, the other end of the bar having an upwardly extending portion and an inwardly extending portion above the other side of the rail base, and a locking member 120 interposed between said inwardly extending portion and the top of the rail base, said bar being sprung from a normal condition and pressing said rail gripping part and said member downwardly and pressing said 130

part engaging the bottom of the rail upwardly in tending to resume said normal condition.

3. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, the other end of the bar having an upwardly extending portion and an inwardly extending portion above the other side of the rail base, and a locking member interposed between said inwardly extending portion and the top of the rail base, said member having an inclined face extending in the direction of the length of the rail and adapted to engage and raise said inwardly extending portion when said member is moved longitudinally of the rail, and said bar being sprung from a normal condition and pressing said rail gripping part and said member downwardly and pressing said part engaging the bottom of the rail upwardly in tending to resume said normal condition.

4. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, and a locking member engaging the other end of said bar and the top of the other side of the rail base, said member having a beveled face extending in the direction of the length of the rail and adapted to engage and raise one end of said bar when said member is moved longitudinally of the rail, said member having a stop projection adapted to engage one side of said bar and limit the movement of said member longitudinally of the rail, and said bar being sprung from a normal condition and pressing said rail gripping part and said member downwardly and pressing said part engaging the bottom of the rail upwardly in tending to resume said normal condition.

5. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, and a locking member engaging the other end of said bar and the top of the other side of the rail base, said member having a beveled face extending in the

direction of the length of the rail and adapted to engage and raise one end of said bar when said member is moved longitudinally of the rail, said member having stop projections on the respective sides of said bar adapted to prevent longitudinal displacement of the member with respect to the bar in one position of the member, and said bar being sprung from a normal condition and pressing said rail gripping part and said member downwardly and pressing said part engaging the bottom of the rail upwardly in tending to resume said normal condition.

6. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, the other end of the bar having an upwardly extending portion and an inwardly extending portion above the other side of the rail base, and a locking member interposed between said inwardly extending portion and the top of the rail base, said member having an inclined face extending in the direction of the length of the rail and adapted to engage and raise said inwardly extending portion when said member is moved longitudinally of the rail, said member having a stop projection adapted to engage one side of said bar and limit the movement of said member longitudinally of the rail, and said bar being sprung from a normal condition and pressing said rail gripping part and said member downwardly and pressing said part engaging the bottom of the rail upwardly in tending to resume said normal condition.

7. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, the other end of the bar having an upwardly extending portion and an inwardly extending portion above the other side of the rail base, and a locking member interposed between said inwardly extending portion and the top of the rail base, said member having an inclined face extending in the direction of the length of the rail and adapted to engage and raise said inwardly extending portion when said member is moved longitudinally of the rail, said member having a stop projection adapted to engage one side of said bar and limit the movement of said member longitudinally of the rail, said member having stop projections on the respective sides of said bar

adapted to prevent longitudinal displacement of the member with respect to the bar in one position of the member, and said bar being sprung from a normal condition and 5 pressing said rail gripping part and said member downwardly and pressing said part engaging the bottom of the rail upwardly in tending to resume said normal condition.

8. The combination with a railroad rail 10 having a base, and a stationary part of a road bed, of an anti-creeper adapted to engage said stationary part and comprising a spring bar extending beneath the rail and provided with a part engaging the bottom of 15 the rail, one end of said bar having a rail gripping part extending over one side of the rail base, the other end of said bar having an upwardly extending portion spaced from the other side of the rail base and an inwardly 20 extending portion above the rail base, and a locking member interposed between said inwardly extending portion and the top of the rail base, said member having a part extending into the space between said upwardly 25 extending portion and the adjacent side of the rail base, and said bar being sprung from a normal condition and pressing said rail gripping part and said member downwardly and pressing said part engaging the bottom 30 of the rail upwardly in tending to resume said normal condition.

9. The combination with a railroad rail having a base, and a stationary part of a road bed, of an anti-creeper adapted to engage said stationary part and comprising a spring bar extending beneath the rail and provided with a part engaging the bottom 35 of the rail, one end of said bar having a rail gripping part extending over one side of the rail base, the other end of said bar having an upwardly extending portion spaced from the other side of the rail base and an inwardly 40 extending portion above the rail base, and a locking member interposed between said inwardly extending portion and the top of the rail base, said member having a part extending into the space between said upwardly 45 extending portion and the adjacent side of the rail base, said member having an inclined face extending in the direction of the length of the rail and adapted to engage and raise said inwardly extending portion when said member is moved longitudinally of the rail, and said bar being 50 sprung from a normal condition and pressing said rail gripping part and said member downwardly and pressing said part engaging the bottom of the rail upwardly in tending to resume said normal condition.

10. The combination with a railroad rail 55 having a base, and a stationary part of a road bed, of an anti-creeper adapted to engage said stationary part and comprising a spring bar extending beneath the rail and provided with a part engaging the bottom 60

of the rail, one end of said bar having a rail gripping part extending over one side of the rail base, the other end of said bar having an upwardly extending portion spaced from the other side of the rail base and an inwardly 70 extending portion above the rail base, and a locking member interposed between said inwardly extending portion and the top of the rail base, said member having a part extending into the space between said upwardly 75 extending portion and the adjacent side of the rail base, said member having an inclined face extending in the direction of the length of the rail and adapted to engage and raise said inwardly extending portion when said member is moved longitudinally of the rail, and said bar being sprung from a normal condition and pressing said rail gripping part and said member downwardly and pressing said part engaging the bottom 80 of the rail upwardly in tending to resume 85 said normal condition.

11. The combination with a railroad rail having a base, and a stationary part of a road bed, of an anticreeper adapted to engage said stationary part and comprising a spring bar extending beneath the rail and provided with a part engaging the bottom 90 of the rail, one end of said bar having a rail gripping part extending over one side of the rail base, the other end of said bar having an upwardly extending portion spaced from the other side of the rail base and an inwardly 95 extending portion above the rail base, and a locking member interposed between said inwardly extending portion and the top of the rail base, said member having a part extending into the space between said upwardly extending portion and the adjacent side of the rail base, said member having an inclined face extending in the direction of the length of the rail and adapted to engage and raise said inwardly extending portion when said member is moved longitudinally of the rail, and said member having a stop projection adapted to engage one side 100 of said bar and limit the movement of said member longitudinally of the rail, said member having stop projections on the respective sides of said bar adapted to prevent longitudinal displacement of the member with respect to the bar in one position of the member, and said bar being sprung from a normal condition and pressing said rail gripping part and said member downwardly and pressing said part engaging the bottom of the rail upwardly in tending to resume said normal condition.

12. The combination with a railroad rail having a base, and a stationary part of a road bed, of an anticreeper comprising a 105

spring bar extending beneath the rail and provided with a part engaging the bottom of the rail, one end of said bar having a rail gripping part extending over one side of the rail base, a locking member engaging the other end of said bar and the top of the other side of the rail base, said member having a beveled face extending in the direction of the length of the rail and adapted to engage and raise one end of said bar when said member is moved longitudinally of the rail, and a stop part adapted to engage said stationary part and clamped between said bar and the bottom of the rail, said bar being sprung from a normal condition and pressing said rail gripping part and said member downwardly and pressing said stop part upwardly in tending to resume said normal condition.

13. The combination with a railroad rail having a base and a stationary part of a road bed, of an anticreeper comprising a spring bar extending beneath the rail and provided with a part engaging the bottom of the rail, one end of said bar having a rail gripping part extending over one side of the rail base, the other end of the bar having an upwardly extending portion and an inwardly extending portion above the other side of the rail base, a locking member interposed between said inwardly extending portion and the top of the rail base, and a stop part adapted to engage said stationary part and clamped between said bar and the bottom of the rail, said bar being sprung from a normal condition and pressing said rail gripping part and said member downwardly and pressing said stop part upwardly in tending to resume said normal condition.

14. The combination with a railroad rail having a base, and a stationary part of a road bed, of an anti-creeper comprising a spring bar extending beneath the rail and provided with a part engaging the bottom of the rail, one end of said bar having a rail gripping part extending over one side of the rail base, the other end of said bar having an upwardly extending portion spaced from the other side of the rail base and an inwardly extending portion above the rail base, a locking member interposed between said inwardly extending portion and the top of the rail base, said member having a part extending into the space between said upwardly extending portion and the adjacent side of the rail base, and a stop part adapted to engage said stationary part and clamped between said bar and the bottom of the rail, said bar being sprung from a normal condition and pressing said rail gripping part and said member downwardly and pressing said stop part upwardly in tending to resume said normal condition.

15. The combination with a railroad rail having a base, and a stationary part of a

road bed, of an anti-creeper adapted to engage said stationary part and comprising a bar extending beneath the rail and provided with a part engaging the bottom of the rail, one end of said bar having a rail gripping part extending over one side of the rail base, and a locking member engaging the other end of said bar and the top of the other side of the rail base, said member having a beveled face extending in the direction of the length of the rail and adapted to engage and raise one end of said bar when said member is moved longitudinally of the rail.

16. The combination with a railroad rail having a base, and a stationary part of a road bed, of an anti-creeper adapted to engage said stationary part and comprising a bar extending beneath the rail and provided with a part engaging the bottom of the rail, one end of said bar having a rail gripping part extending over one side of the rail base, the other end of the bar having an upwardly extending portion and an inwardly extending portion above the other side of the rail base, and a locking member interposed between said inwardly extending portion and the top of the rail base, said member having an inclined face extending in the direction of the length of the rail and adapted to engage and raise said inwardly extending portion when said member is moved longitudinally of the rail.

17. The combination with a railroad rail having a base, and a stationary part of a road bed, of an anti-creeper comprising a bar extending beneath the rail and provided with a part engaging the bottom of the rail, one end of said bar having a rail gripping part extending over one side of the rail base, a locking member engaging the other end of said bar and the top of the other side of the rail base, said member having a beveled face extending in the direction of the length of the rail and adapted to engage and raise one end of said bar when said member is moved longitudinally of the rail, and a stop part adapted to engage said stationary part and clamped between said bar and the bottom of the rail.

18. The combination with a railroad rail having a base, and a stationary part of a road bed, of an anti-creeper comprising a bar extending beneath the rail and provided with a part engaging the bottom of the rail, one end of said bar having a rail gripping part extending over one side of the rail base, the other end of the bar having an upwardly extending portion and an inwardly extending portion above the other side of the rail base, a locking member interposed between said inwardly extending portion and the top of the rail base, said member having an inclined face extending in the direction of the length of the rail and adapted to engage and raise said inwardly extending portion

- when said member is moved longitudinally of the rail, and a stop part adapted to engage said stationary part and clamped between said bar and the bottom of the rail.
19. The combination with a railroad rail having a base, and a stationary part of a road bed, of an anti-creeper comprising a spring bar extending beneath the rail and having rail gripping parts extending over the respective sides of the rail base, and a stop part adapted to engage said stationary part and having a wedge formed thereon and clamped between said bar and the bottom of the rail, said wedge being formed between side faces of the stop part converging in the direction away from said stationary part, said bar being sprung from a normal condition and pressing said rail gripping parts downwardly and pressing said wedge upwardly in tending to resume said normal condition.
20. The combination with a railroad rail having a base, and a stationary part of a road bed, of an anti-creeper comprising a
- spring bar extending beneath the rail and having rail gripping parts extending over the respective sides of the rail base, and a stop part adapted to engage said stationary part and having a wedge formed thereon and clamped between said bar and the bottom of the rail, said wedge being formed between side faces of the stop part converging in the direction away from said stationary part, said bar being sprung from a normal condition and pressing said rail gripping parts downwardly and pressing said wedge upwardly in tending to resume said normal condition, and said stop part having a downwardly extending stop projection between which and said stationary part said bar is located.

In testimony whereof I affix my signature in presence of two witnesses.

DAVID F. VAUGHAN.
